UNITED STATES PATENT OFFICE.

BERNHARD ABELES, OF NEW YORK, N. Y., ASSIGNOR TO SCHEUER & BROTHER, OF SAME PLACE.

DESIGN FOR A BELT-BODY.

SPECIFICATION forming part of Design No. 34,460, dated April 30, 1901.

Application filed March 22, 1901. Serial No. 52,438. Term of patent 7 years.

To all whom it may concern:

Be it known that I, BERNHARD ABELES, a citizen of the United States, residing at New York, borough of Manhattan, and State of New York, have invented and produced a new and original Design for Belt-Bodies, of which the following is a specification, reference being had to the accompanying drawings, in which—

Figure 1 is a plan view showing my design for belt-bodies, and Fig. 2 is a transverse section thereof on line 2 2, Fig. 1.

The leading feature of my design is a series of longitudinally-arranged oblong figures, spaced apart sidewise as well as longitudinally, and a series of transverse oblong figures alternating with the aforesaid figures, so that an interlaced effect is produced, such

oblong figures terminating at plain parallel longitudinal borders.

A indicates the series of longitudinally-arranged figures, and B the series of transverse figures. The outermost figures B run to plain borders C C, which extend along the edges of the belt-body.

What I claim is—

The design for a belt-body, as shown and described.

In testimony that I claim the foregoing as my invention I have signed my name in presence of two subscribing witnesses.

BERNHARD ABELES.
